UNITED STATES PATENT OFFICE.

MAXWELL E. PESTER, FREDERICK C. PORTER, AND WILLIAM G. HOFMAN, OF BRIDGEPORT, CONNECTICUT.

GAME APPARATUS.

1,370,479.

Specification of Letters Patent.

Patented Mar. 1, 1921.

Application filed February 3, 1920. Serial No. 355,912.

To all whom it may concern:

Be it known that we, MAXWELL E. PESTER, FREDERICK C. PORTER, and WILLIAM G. HOFMAN, citizens of the United States, and residents of Bridgeport, in the county of Fairfield and State of Connecticut, have invented certain new and useful Improvements in Game Apparatus, of which the following is a specification.

10 This invention relates to an improved form of game apparatus including a table and a series of balls to be rolled thereon, such as is adapted to be used in public amusement places.

15 The object of the invention is to provide an improved form of game apparatus including a table having a series of runways leading to a conical shaped receptacle, and a series of balls which may be simultaneously played in the runways by a number of persons, each with a view of being the first to get the ball in the receptacle. Further to include a ball elevating means whereby one or more of the balls may be raised 20 to the top of the game table after being played, also to provide a signal for the players, an opening and closing means for the runway, a control lever for operating both the opening and closing means, the elevator and signaling device.

25

30

With these and other objects in view the invention resides and consists in the construction and novel combination and arrangements of parts hereinafter more fully described, illustrated in the accompanying drawings, and pointed out in the claims hereto appended, it being understood that various changes in the form, proportion, size and minor details of construction within the scope of the claims may be resorted to without departure from the spirit or sacrificing any of the advantages of the invention.

Similar characters of reference denote like or corresponding parts throughout the several figures of the accompanying drawings forming a part of this specification, and upon which,

Figure 1 is a plan view of our improved game apparatus including a few balls idly positioned thereon.

Fig. 2 shows a plan view of the underside of the table, broken away.

Fig. 3 is a central vertical cross section of the game table as shown in Fig. 1.

Fig. 4 is an enlarged detail cross sectional view of a portion of the table and receptacle ring shown in Fig. 3, and

Fig. 5 is an enlarged detail plan view of the parts shown in Fig. 4.

As will be noted from the drawings, the game apparatus is constructed in the form of a round table, and obviously may be made up in any desired size according to the available space to be occupied and the number of players to be accommodated. The top of the table is of a general conical shape with a series of runways leading from the outer edge portions to the center and is supported upon legs, and provided with an operating lever forming a controlling means whereby the attendant may signal the players and open the runways of the machine. The players may be either seated or standing around the table in position to operate the balls at a given signal, by rolling the same down inclined grooves, through the holes and into a receptacle where they are guided into alignment. The object of the game being to roll the balls with such judgment and skill as to get the first ball through the machine.

Referring in detail to the characters of reference marked upon the drawings, 6 represents the top body portion of the table and 7 the several legs supporting the same. These legs, as will be noted, each include adjustable means in the form of a screw 8 which is secured in the upper end of each leg and extend slightly up into the body of the table. A nut 9 is adjustably mounted upon each of these screws and serves to directly engage and support the underside of the table. These devices form adjustable means for the table whereby the same may be set perfectly level irrespective of whether or not the floor is level, and so as to insure a uniform pitch to the several grooves in the inclined top portion of the table. The lower portion of the legs may be braced by 100 cross members 10 and the center of these braces are further supported by a post 11. An annular groove 12 is formed in the top side of the outer edge portion of the table to contain the balls 13 when not in use. In 105 this top surface of the table we also position

a series of small spirit levels 14 which are properly set to aline with the top surface of the table and whereby the same may be properly leveled.

5 Runways 15 are formed in the incline top surface of the table and extend from the outer edge portion to the central portion and are all similarly curved. A series of holes 16 are formed through the central 10 portion of the table one at the end of each runway so that when the balls have run down the incline grooves they will drop through the holes and in the receptacle 17 hung upon the underside of the central portion of the table.

15 This receptacle is of a conical shape and serves to receive the balls as they drop through the series of holes and to guide them down and out of the outlet 18 and 20 into the runway 19 positioned immediately beneath the outlet and supported by the hangers 20 and 21. The conical portion of the receptacle as shown is formed of sheet metal and is carried by an annular ring 22 25 which includes an outwardly disposed annular flange slidably mounted in guides 23 secured to the under side of the table. This ring further carries an inwardly disposed portion that is provided with a 30 series of vertical holes, spaced to register with the holes 16 in the table, so that when positioned to aline therewith, will form an unobstructed passage through which the balls may drop into the receptacle. On the other hand when the flanged ring including the conical receptacle is turned slightly the holes in the ring are moved out of register with the upper holes 35 so as to close the passages formed thereby. 40 Upon this inwardly disposed portion of the ring is an extended hub portion 24 to which further parts are attached in a manner to be carried therewith. The glass plate 25 serves to cover and incase the receptacle in a way to admit light, so as to see in, if necessary. The several braces 26 whose lower ends are secured to the hub are bound together by a wire loop 27 and serve to support the holder 28 carrying 45 50 electric lamps 29 which are automatically turned on as the machine is set for operation. 30 represents cushions that are secured to the peripheral surface of the hub in position to aline with the several runways and against which the balls hit before dropping through the holes. A series of stops 31 are also attached to the periphery of the hub and positioned intermediate of the cushions so as to also aline with the runways when 55 60 the machine is closed against playing.

32 represents an operating lever which is secured to the movable receptacle ring and whereby the latter are oscillated for opening and closing the machine. This lever is 65 also positioned to open and close an electric

cal circuit whereby a signal bell 33 is operated and the lights 29 turned on or off. 34 represents a contact plate attached to the underside of the table in line of movement with the lever 32 which serves as a means 70 for opening and closing the circuit. These electrical appliances would be connected with either batteries or a power circuit.

As before stated, our game table also includes an elevator 35 which is normally positioned in line with the lower end of the runway 19 to receive the first ball of the series to run down. Beneath the elevator we also provide a basket 36 to receive the remaining balls which roll into it after the 80 elevator is raised. This elevator is supported in a frame 37 hung from the table and forming a guide in which the elevator may be raised and lowered and is operated by the lever 32 and is connected therewith by 85 a cord 38 that is guided over the rolls 39 and 40 and through the eye 41 of the arm 42. This connects the elevator with the operating lever so that when the lever is in the position shown in full lines the elevator is 90 lowered to receive the ball and when the lever is thrown over to close the machine the elevator would be raised so as to discharge the ball in the annular groove.

Having thus described our invention, 95 what we claim and desire to secure by Letters Patent, is—

1. A game apparatus of the class described, comprising a table having a series of holes through its central portion and a 100 series of runways leading to said holes, a receptacle beneath the holes to receive the balls through the holes and to form them in alinement, an opening and closing device for the holes, and a series of balls to be 105 played through said runways and holes.

2. A game apparatus of the class described, comprising a table having a series of inclined runways, a receptacle positioned in the central portion of the table and communicating with the runways, a rotatable member with means for opening and closing the passages from the runways to the receptacles, a runway positioned to receive the balls from the receptacle, and means to 110 lift the balls to the top of the table.

3. A game apparatus of the class described, comprising a table having a series of holes through its central portion and a 120 series of runways leading to said holes, a series of balls to be played through said runways and holes, a cushioning device in alinement with the end of each runway, a single receptacle beneath the holes to receive the balls from the table and having 125 a contracted outlet to discharge one ball at a time.

4. A game apparatus of the class described, comprising a table having a series of inclined runways and an opening through 130

the table at the foot of each runway, a rotatable carrier mounted on the central portion of the table, a conical shaped receptacle secured to the carrier beneath the openings, means carried by the carrier to open and close the passages from the runways to the receptacle, a lever and connections therewith to operate the carrier and its parts for opening and closing the runways.

Signed at Bridgeport in the county of 10
Fairfield and State of Connecticut this 31st
day of January, A. D. 1920.
